UNITED STATES PATENT OFFICE.

FREDERICK C. SHEARER, OF SAN ANTONIO, TEXAS.

TIE-MOLD.

1,331,944.

Specification of Letters Patent. Patented Feb. 24, 1920.

Application filed June 25, 1918. Serial No. 241,798.

To all whom it may concern:

Be it known that I, FREDERICK C. SHEARER, a citizen of the United States, residing at San Antonio, in the county of Bexar and 5 State of Texas, have invented certain new and useful Improvements in Tie-Molds; and I do hereby declare the following to be a full, clear, and exact description of the invention, such as will enable others skilled in 10 the art to which it appertains to make and use the same.

This invention relates to improvements in tie molds and has for one of its objects the provision of a device of this character especially adaptable for forming concrete railroad ties of the character set forth in 15 my Patent #1,229,154.

Another object of this invention is the provision of means for forming the cushion 20 block recesses and the lateral depressions for receiving the securing bars.

A further object of this invention is the provision of means for forming the V-shaped rib to the tie.

25 A still further object of this invention is the provision of means for supporting the reinforcing elements or tie bars in their proper place when pouring the cement or other material and which can be readily removed after the partial setting of the cement.

30 A still further object of this invention is the provision of a tie mold of the above stated character, which shall be simple, durable and efficient, and which may be manufactured and sold at a comparatively low cost.

35 With these and other objects in view as will become more apparent as the description proceeds, the invention consists in certain novel features of construction, combination, and arrangement of parts as will be hereinafter more fully described and claimed.

40 For a complete understanding of my invention reference is to be had to the following description and accompanying drawings, in which:

45 Figure 1 is a vertical sectional view of a tie mold constructed in accordance with my invention,

Fig. 2 is a top plan view of the same,

Fig. 3 is a transverse sectional view taken on the line 3—3 of Fig. 1,

50 Fig. 4 is a similar view taken on the line 4—4 of Fig. 1,

Fig. 5 is a fragmentary perspective view of one of the side boards,

Fig. 6 is a perspective view of the side and end boards illustrating the manner of 60 securing them together,

Fig. 7 is a perspective view of the pallet,

Fig. 8 is a transverse sectional view taken on the line 8—8 of Fig. 1, and

Fig. 9 is a side elevation of the finished 65 tie.

Referring in detail to the drawings, the numeral 1 indicates as an entirety a mold frame consisting of side and end members 2 and 3. The side members 2 are provided 70 with grooves 4 adjacent their ends to slidably receive ribs 5 formed upon the ends of the end members 3. Bolts 6 extend through the ends of the side members 2 outwardly of the end members 3 and are 75 slotted to receive keys 7. The side members 2 have formed thereon oppositely disposed pairs of lugs 8 which are adapted to form depressions 9 in the side faces of the tie 10. A pallet 11 is positioned within the mold 80 frame 1 and consists of a bottom member 12 having formed upon its edges beveled beads 13 that are adapted to form the beveled edges 14 of the tie 10.

The bottom member or board 12 has 85 formed thereon rectangular blocks 15 which are positioned between the pairs of lugs 8 and are adapted to form the cushioning block recesses 16 of the tie 10. By having the blocks 15 in engagement with the lugs 8 90 provides means wherein the recesses 16 will be in communication with the grooves 9 in the finished product as illustrated in Fig. 9.

The side members 2 are provided with a plurality of openings 17 located directly 95 above the lugs 8 to receive supporting members 18. The supporting members 18 are adapted to be inserted through the openings 17 for the purpose of supporting and holding reinforcing elements or tie members 19 100 in their proper position between the side members 2 when pouring the cement into the mold frame. The supporting members can be readily removed when the cement or similar material has become partially set leaving 105 the reinforcing elements embedded within the cement.

A rib forming plate 20 is positioned between the side members 2 of the mold frame 1 after the same has been filled with the cement or similar material. The plate 20 has 110 its inner face curved in arcuate formation

longitudinally and transversely is inclined in V-shape formation as illustrated at 21, so that when the cement has become set a substantially V-shaped rib 22 will be formed 5 within the tie 10 intermediate its ends as illustrated in Fig. 9. The plate 20 is held in position by suitable clamps 23 extending about the mold frame 1 and which holds the pallet 11 in position.

10 While I have shown and described the preferred embodiment of my invention, it will be understood that minor changes in construction, combination, and arrangement of parts may be made without departing 15 from the spirit and scope of the invention as claimed.

Having thus described my invention, what I claim is:

1. A mold including side and end walls, 20 pairs of spaced lugs formed on the side walls, a pallet associated with the walls, and spaced blocks secured to the pallet for forming recesses in the molded article and fitting between the pairs of lugs for aiding 25 in preventing movement of the pallet in relation to the wall.

2. A mold including side and end walls, pairs of spaced lugs formed on the side walls, a pallet associated with the walls, 30 spaced blocks secured to the pallet for forming recesses in the molded article adjacent

each end and said blocks fitted between the pairs of lugs for aiding in preventing movement of the pallet in relation to the wall, said lugs forming grooves in the molded 35 article and communicating with the recesses, pairs of rods removably secured to the side walls and disposed on each side of the blocks, and reinforcing members supported by said rod and having their ends disposed 40 at right angles and their intermediate portions curved arcuately.

3. A mold including side and end walls, pairs of spaced lugs formed on the side walls, a pallet associated with the walls, 45 spaced blocks secured to the pallet and fitted between the pairs of lugs, supporting elements carried by the side walls, reinforcing members supported by said supporting elements and having their intermediate portions of arcuate shape, a rib forming plate 50 associated with the side walls and having its inner face curved in arcuate formation longitudinally and inclined in V-shaped formation transversely, and clamps securing said 55 plate to the side walls.

In testimony whereof I affix my signature in presence of two witnesses.

FREDERICK C. SHEARER.
